MACHINE AND METHOD FOR MAGNETICALLY TURNING SPRINGS IN POCKETS

Robert H. Stevens, Detroit, Mich., assignor to The Murray Corporation of America, Detroit, Mich., a corporation of Delaware

Application June 29, 1948, Serial No. 35,793

11 Claims. (Cl. 226—18)

1

This invention relates to spring turning means, and particularly to a machine and method for turning springs from a position crosswise of a pocket to a position lengthwise thereof.

Difficulty has been experienced in the art of cushion construction caused by the necessity for turning springs after they are inserted in pockets from a position crosswise of the pockets to a position lengthwise thereof.

In constructing a spring cushion, lengths of fabric are folded and stitched crosswise to provide adjacent pockets in which coil springs are inserted and retained when the folded fabric is stitched lengthwise for closing the open ends of the pockets. A plurality of rows of the springs in fabric pockets are utilized for forming the spring supporting portion of the cushion. To provide sufficient material at the open ends of the pockets, the springs are placed therein in compressed position crosswise of the pocket and it is necessary after the stitching operation to manipulate the springs to turn them from a crosswise to a lengthwise position. Heretofore this was done by hand, the springs being individually turned in the pocket, which required quite a degree of skill and which was extremely costly.

The present invention pertains to a machine through which the strips of material having the pockets and springs therein are fed to be operated on by one or a plurality of sets of electric magnets having pole shoes disposed in such a position as to cause the spring to rotate within the pocket 90° from a position crosswise thereof to a position lengthwise thereof.

In the machine herein illustrated, means are provided for engaging at least one edge of the strips for advancing the fabric and springs through a tunnel between the pole shoes and for holding the fabric material from turning with the springs when the springs are turned by the magnetic field. The plurality of sets of magnets and pole shoes are illustrated so that if in passing through one magnetic field the spring for some reason does not completely turn to be capable of expanding into a position lengthwise of the pocket, this would occur for a certainty when passing through one or the other adjacent fields.

Accordingly, the main objects of the invention are: to provide a device for turning the springs in adjacent fabric pockets from a position crosswise thereof to one lengthwise thereof; to provide a magnetic field disposed at an angle to the axis of a spring for causing the spring to turn to a position with the axis parallel to the field

so that it can expand to a position lengthwise of a pocket containing the spring; to provide means for engaging one edge of a fabric having a plurality of pockets containing coil springs disposed crosswise thereof for advancing the fabric and springs through one or a plurality of magnetic fields disposed at an angle to the axis of the springs for turning the springs to permit them to expand into a position lengthwise of the pockets; and, in general, to provide a device and method for turning springs in pockets which is simple in construction, positive in operation and economical of manufacture.

Other objects and features of novelty of the invention will be specifically pointed out or will become apparent when referring, for a better understanding of the invention, to the following description taken in conjunction with the accompanying drawings, wherein:

20 Fig. 1 is a plan view of a device for turning springs in fabric pockets embodying features of this invention;

Fig. 2 is an enlarged sectional view of the structure illustrated in Fig. 1, taken on the line 2—2 thereof;

Fig. 3 is a diagrammatical view of the structure illustrated in Fig. 2;

Fig. 4 is a diagrammatical view of structure, similar to that illustrated in Fig. 3, showing a further form thereof;

Fig. 5 is a diagrammatical view of structure, similar to that illustrated in Figs. 3 and 4, showing a still further form of the invention;

Fig. 6 is a broken plan view of fabric material having pockets therein containing springs disposed crosswise of the pockets;

Fig. 7 is a sectional view of the structure illustrated in Fig. 6;

Fig. 8 is a view of structure, similar to that illustrated in Fig. 6, with the springs disposed lengthwise of the pockets after the turning operation; and

Fig. 9 is a sectional view of the structure illustrated in Fig. 8, taken on the line 9—9 thereof.

In Figures 6 and 7, fabric material 10 is illustrated as being folded upon itself and stitched along the lines 11 to form pockets 12 in which coil springs 13, to be employed for making a cushion, are disposed. The coil springs are positioned crosswise in the pockets 12 to leave the open ends 14 of the pockets disposed some distance from the spring so that it may be stitched along a line 15 for closing the pockets. After the stitching operation, it is necessary to turn the

springs from a crosswise position, as illustrated in Figs. 6 and 7, to a position lengthwise thereof, as illustrated in Figs. 8 and 9, wherein the springs are expanded to a desired height. A plurality of the lengths of the fabric and springs are secured together to form a spring unit for the cushion. Substantial time was required for a skilled operator to turn each individual spring from the position crosswise of the pocket to a position lengthwise thereof.

The present invention pertains to the use of a magnetic field disposed at an angle to the axis of the advancing springs to cause the springs to be rotated or tilted from a position crosswise of the pockets to an angular position from which the springs expand to a position lengthwise of the pockets.

Referring to Figs. 1 and 2, specifically, a device is therein illustrated embodying a table having a top 16 and a plurality of legs 17 for supporting a housing 18 which forms a tunnel 19 through which the fabric material 10, containing the pockets and springs, as illustrated in Fig. 6, may be advanced. The top 16 and housing 18 are preferably made of nonmagnetic materials so as not to influence the magnetic field imposed thereon. The ends of the top 16 support a pair of V pulleys 21 and 22 for driving a belt 23, with the upper part thereof passing through the tunnel 19 and the lower part thereof passing thereunder. The top of the belt is provided with a plurality of pointed hooks 24 over which the fabric ends 25 beyond the line of stitching may be secured.

The tunnel has along one edge thereof an upstanding flange 26 for retaining the belt within a channel 27 formed thereby along one edge of the tunnel. A shaft 28 drives the pulley 22 from a pulley 29 connected by a belt 31 to a suitable source of power, such as by a motor, not herein illustrated. The shaft 28 is supported by a bearing 32 attached to the adjacent leg 17 in a conventional manner.

One or a plurality of magnets 34 and 35 are supported by a plate 36 on the legs 17 and by a similar plate 37 on brackets 38 attached to the legs 17 on the opposite side of the device. The poles 40 and 41 of the magnets having coils 42 and 43 thereon are provided with pole shoes 44 and 45, respectively, which are disposed at opposite top and bottom corners of the tunnel 19, as illustrated more specifically in Figs. 2 and 3. The coils 42 and 43 are so wound as to produce an attractive force to the ends of the springs to cause the top of the spring to move to the right, as viewed in the figures, as the bottom of the spring is moved to the left. This turning or tilting movement is sufficient to cause the spring to be rotated an amount from which it may expand within the pockets to a position lengthwise thereof. The pins 24 hold the one edge of the fabric from turning with the spring, while the flange 26 prevents the belt and fabric from being drawn inwardly toward the center of the tunnel 19 due to the magnetic force acting upon the spring.

In Figure 1, five sets of magnets 34 and 35 are illustrated which permit rapid advancement of the fabric and springs therethrough. In case the magnetic field of the first set of magnets does not sufficiently turn the spring, the next adjacent set, or the set thereafter, will provide magnetic fields to operate upon the springs so that by the time the spring passes through all of the individual fields, they will be disposed in length-

wise position of the pocket, as illustrated in Figs. 8 and 9 of the drawing.

In Fig. 4 a diagrammatic view of pole and pole pieces is illustrated which are similar to those of Fig. 3, with the exception that the poles are aligned diagonally through the spring and the pole shoes 48 and 49 extend outwardly thereof to project over substantially one-half of the spring. The pole shoes exert a substantial turning moment on the spring to cause it to be shifted within the pocket sufficiently to permit the tension of the spring to move it to a position lengthwise of the pocket.

In Fig. 5 a similar diagrammatic arrangement of pole shoes and magnet is illustrated, that wherein pole shoes 52 and 53 are disposed in out of aligned relation in opposite edges of the top and bottom of the spring. The pole shoes extend from a pole 54 disposed on an arc therebetween on which a single coil 55 is provided. This provides a closed magnetic circuit about the spring which is capable of supplying a substantial energy to turn the spring within the pocket.

In any of the arrangements herein illustrated, the lengths of fabrics containing springs in pockets are fed through the tunnel 19 while holding the fabric and pockets against turning while the springs are turned by the flux of the magnetic field or fields when the springs are advanced therethrough. As pointed out hereinabove, several sets of magnets may be employed on the device so that the spring will be subjected to the flux of several magnetic fields as the strip of fabric is advanced therethrough to make certain that the springs are completely turned and nested within the pocket as it expands to a desired lengthwise position therein. While reference has been made herein to pockets which are formed and closed by stitching, it is to be understood that latex, glues and other adhering substances, known in the art to be suitable, may be utilized in place of the stitching for forming and/or closing the pockets.

What is claimed is:

1. A device for turning springs in fabric pockets adjacently disposed in a strip of material, embodying holding and advancing means for at least one edge of the fabric to prevent it from turning when the springs are turned within the pockets, and an electromagnet providing a force disposed at an angle to the axis of the spring for causing the spring to turn within the pockets when passing through the field.

2. In a device for turning springs in pockets including, in combination, a supporting structure, means on the supporting structure for advancing the pockets and springs through the device, a set of magnets for producing a magnetic field disposed at an angle to the axis of the springs as the springs are advanced therethrough for turning the springs in the pockets.

3. In a device for turning springs in adjacent fabric pockets including, in combination, a supporting structure for advancing the pockets and springs through the device, a plurality of sets of magnets for producing magnetic fields disposed at an angle to the axis of the springs as the springs are advanced therethrough for turning the springs in the pockets.

4. A device for operating on springs for turning them from a position crosswise to a position lengthwise of pockets disposed in strips of fabrics which includes, in combination, a supporting

structure, a tunnel provided on the supporting structure, a belt driven from said supporting structure through said tunnel, means on said belt for engaging one edge of said fabric in which the springs are disposed in crosswise position for advancing the pockets through said tunnel and for holding the fabric against turning movement with the springs, and a set of magnets having pole pieces disposed adjacent to said opposite corners of said tunnel to provide a magnetic field so disposed as to cause opposite ends of the spring to be drawn toward the pole pieces to thereby turn the springs from said crosswise position so that the springs may expand to a position lengthwise of the pockets.

5. A device for operating on springs for turning them from a position crosswise to a position lengthwise of adjacent pockets provided in strips of fabric which includes, in combination, a supporting structure, a tunnel provided on the supporting structure, a belt driven from said supporting structure through said tunnel, means on said belt for engaging said fabric in which the springs are disposed in crosswise position for advancing the pockets through said tunnel and for holding the pockets against turning movement with the springs, a plurality of sets of magnets having pole pieces disposed adjacent to opposite corners of said tunnel to provide magnetic fields disposed at an angle to the axis of the springs for causing opposite ends of the springs to be drawn toward the pole pieces to thereby turn the springs from said crosswise position so that the springs may expand to a position lengthwise of the pockets.

6. In a device for turning springs from a crosswise position to a lengthwise position in adjacent pockets in a strip of fabric material including, in combination, supporting means, a tunnel carried by said supporting means, a continuous belt having one portion driven through said tunnel, fabric engaging means provided on said belt for advancing said fabric and springs through the tunnel and for holding the fabric when the springs are turned therein, and an electromagnet disposed adjacent to said tunnel for providing a magnetic field at an angle to the axis of the spring for causing opposite ends of the springs to be moved in opposite directions to thereby shift the springs within the pocket and permit them to expand into a position lengthwise of the pockets.

7. In a device for turning springs from a crosswise position to a lengthwise position in adjacent pockets in a strip of fabric material including, in combination, supporting means, a tunnel carried by said supporting means, a continuous belt having one portion driven through said tunnel, fabric engaging means provided on said belt for advancing said fabric and springs through the tunnel and for holding the fabric when the springs are turned therein, and an electromagnet disposed adjacent to said tunnel for providing a magnetic field at an angle to the axis of

the spring for causing opposite ends of the springs to be moved in opposite directions to thereby shift the springs within the pocket and permit them to expand into a position lengthwise of the pockets, said holding means embodying a plurality of hooks having sharp ends over which the fabric is secured.

8. In a device for turning springs from a crosswise position to a lengthwise position in adjacent pockets in a strip of fabric material including, in combination, supporting means, a set of magnets carried by said supporting means having pole shoes disposed in spaced relation, a continuous belt having one portion driven through an area adjacent to said pole shoes, fabric engaging means provided on said belt for securing and advancing said fabric and springs through a magnetic field provided between said pole shoes and for holding the fabric when the springs are turned therein a sufficient amount by said magnetic field to permit the springs to expand to a position lengthwise of the pockets.

9. The method of turning springs from a crosswise position to a lengthwise position in pockets in a fabric strip which includes the steps: of providing a magnetic field, of advancing the fabric material and springs through said magnetic field, and of holding said fabric material against substantial movement while the magnetic field causes the springs to turn within the pockets an amount to permit them to expand to a position lengthwise of the pockets.

10. The method of turning springs in pockets provided in fabric material which includes the steps: of providing a magnetic field disposed crosswise of the axis of the springs in the pockets, and of advancing the fabric and springs through the magnetic field which turns the springs a sufficient amount to permit them to expand to a position lengthwise of the pockets.

11. The method of turning springs in pockets provided in fabric material which includes the steps: of providing a magnetic field disposed crosswise of the axis of the springs in the pockets, of advancing the fabric and springs through the magnetic field which turns the springs a sufficient amount to permit them to expand to a position lengthwise of the pockets, and of retaining said fabric material against substantial movement laterally of said advancing movement during the turning of the springs.
